(57) **CLAIM**

We claim the ornamental design for a portable electronic device, as shown and described.

DESCRIPTION

FIG. 1 is a front perspective view of a portable electronic device showing our new design according to a first embodiment;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged cross-sectional view thereof taken through line 9-9 in FIG. 2;

FIG. 10 is an enlarged cross-sectional view thereof taken through line 10-10 in FIG. 2;

FIG. 11 is a front perspective view of a portable electronic device showing our new design according to a second embodiment;

FIG. 12 is a front view thereof;

FIG. 13 is a rear view thereof;

FIG. 14 is a left-side view thereof;

FIG. 15 is a right-side view thereof;

FIG. 16 is a top view thereof;

FIG. 17 is a bottom view thereof;

FIG. 18 is a rear perspective view thereof;

FIG. 19 is an enlarged cross-sectional view thereof taken through line 19-19 in FIG. 12; and,

FIG. 20 is an enlarged cross-sectional view thereof taken through line 20-20 in FIG. 12.

(Continued)

The broken lines in the figures depict portions of the portable electronic device which form no part of the claimed design.

1 Claim, 16 Drawing Sheets
